UNITED STATES PATENT OFFICE,

CHARLES PERKES, OF PHILADELPHIA, PENNSYLVANIA.

DESIGN FOR A PUMP-CASING AND BRACKET.

SPECIFICATION forming part of Design No. 28,379, dated March 15, 1898.

Application filed May 16, 1897. Serial No. 636,793. Term of patent 7 years.

To all whom it may concern:

Be it known that I, CHARLES PERKES, a citizen of the United States, residing at Philadelphia, in the county of Philadelphia and State of Pennsylvania, have invented and produced a new and original Design for Pump-Casings, of which the following is a specification, reference being had to the accompanying drawing, forming a part thereof.

10 The drawing represents a perspective view of my original design.

The leading feature of my design comprises an upright pump-casing with a lateral extension having a valve-casing at the outer end thereof and an intermediate extension of the lateral extension also provided with a valve-casing and a bracket supporting said elements.

1 represents a pump-casing.

2 represents a lateral extension. 3 represents the valve-casing at the outer end thereof.

4 represents the intermediate vertical extension, and 5 a valve-casing at the outer end thereof.

The base of the pump-casing is provided with a casting 6, from which depends a bracket extension 7, provided with a base-plate 8.

Having described my invention, what I claim as new, and desire to secure by Letters Patent, is—

The design for a pump-casing and bracket, substantially as shown and described.

In testimony whereof I hereunto affix my signature in the presence of two witnesses.

CHARLES PERKES.
